UNITED STATES PATENT OFFICE.

THOMAS C. DE VORE, OF CHICAGO, ILLINOIS.

AIR VALVE.

Application filed July 19, 1923. Serial No. 652,631.

To all whom it may concern:

Be it known that I, THOMAS C. DE VORE, a citizen of the United States, and a resident of the city of Chicago, county of Cook, 5 and State of Illinois, have invented certain new and useful Improvements in Air Valves, of which the following is a specification.

My invention relates to new and useful improvements in air valves, and has for its 10 principal object the provision of an improved construction of this character which will be highly efficient in use, the present invention constitutes an improvement over that disclosed in my prior application filed 15 in the United States Patent Office, on or about April 11, 1922, Serial No. 551,488.

A further contemplation of the invention is the provision for automatically closing the valve at a predetermined degree of heat 20 and for automatically opening the valve when the degree of heat decreases. In this connection, and to carry these objects into effect, I provide tubular members carried by a hanger and an adjustable support, 25 formed of such material that is capable of expanding and contracting when subject to heat and such expansion and contracting being determined by the degrees of the heat.

A further object of my invention is the 30 provision to compensate excess expansion of the valve closing means after the valve has been closed.

Other objects will appear hereinafter.

The invention consists in the combinations 35 and arrangements of parts hereinafter described and claimed.

The invention will be best understood by reference to the accompanying drawings forming a part of this specification, and in 40 which,

Fig. 1 is a vertical sectional detail view of an air valve embodying the invention,

Fig. 2 is a top plan view of the same,

Fig. 3 is a sectional detail view of the 45 same taken substantially on line 3-3 of Fig. 1,

Referring to the drawings showing the preferred form of construction, A represents an air valve embodying the invention 50 and comprises a cylindrical body 5 open at its lower end, said opening being closed by a base cap 6 having a lateral projection 7 which is adapted to be screw-threaded in the opening of a radiator, (not shown) with 55 which the device is associated. The upper end of the cylindrical body 5 is dome-

shaped, as shown, and carries a valve seat 8 having a central passage 9 formed therethrough, the inner wall portions of said opening 9, that is the portion extending into 60 the cylindrical body 5, being tapered outwardly as indicated at 10. The valve seat 8, is screw-threaded through an opening 10' formed in the top-most or dome-shaped portion of the cylindrical body and is provided with a flange 11 adapted to seat on an annular projection or rib 12 extending around the walls of the opening.

The opening 10' is provided with a closure member 13 which in this instance is in 70 the form of a cylindrical cap having a vent 14 projecting laterally and downwardly from the side of the cap in spaced relation with respect to the dome-shaped portion of the cylindrical body 5, as shown.

Arranged in the base cap 6 is a disc-shaped support 15 carried by an adjustable screw 16 passing through a stuffing box 17. The disc 15 is arranged and adapted to support a tubular member 18 having its side 80 walls perforated and formed of such material that is capable of expanding and contracting when subject to heat. The tubular member 18 is strengthened at its upper edge by an annular channel-shaped ring member 85 19 which carries a hanger 20 formed of such material as is capable of expanding and contracting when subject to heat, but which in this instance, is formed of such material

that will withstand a greater degree of heat 90 than the tubular member 18. The hanger 20 in turn supports and carries a second perforated tubular member 21 arranged within the member 18 as shown, and formed of the same material. The upper edges of the 95 tubular member 21 are also reenforced by a channel-shaped ring member 22 which carries a hanger 23 similar to the hanger 20 and formed of the same material. The

hanger 23 carries a central core 24 formed 100 of material that will not expand or contract when subject to heat or of material having a relatively small co-efficient of expansion, and the core is arranged and adapted to carry a valve stem 24' which works in the tapered portion of the opening 9 of the valve seat and which is adapted to close said opening when the tubular members 18 and 21 expand. However, if desired, the core 24 can be formed of material similar 105 to the material from which the tubular members are formed. The valve stem 24'

110

carries a dish-shaped annular member 25 which serves the purpose of a baffle plate for directing the steam or water vapor against the perforated tubular members 18 and 21. To prevent the valve stem 24', from becoming wedged in the opening 9, I provide an expansion spring 26 which embraces the valve stem and seats against the valve seat 8 and baffle plate 25.

10 I also provided a provision to permit excess expansion of the tubular members 18 and 21, should the members continue to expand due to the heat after the valve is closed. This provision includes a disc 27 having a threaded stud 28 adapted to be threaded in a socket 29 formed in the lower end 30 of the core 24. Abutting the disc 27 and the horizontal portion 31 of the hanger 23 is a spring member 32. This arrangement is such that after the valve has been closed due to the expansion of the tubular members the spring member 32 will permit the continuation of expansion thereby preventing rupture of the tubular members and hangers. When the tubular members contract to permit opening of the valve the compression of the spring member 32 is released as will be readily understood. It is intended that the tension of the spring member 32 be somewhat greater than the tension of the spring member 26 so that the spring member 32 will not be brought into action, that is compressed, until the valve is closed.

In use, my air vent as herein illustrated and described, is mounted in the usual way on a radiator or the like through the medium of the stem 7 and when the steam or water vapor from the radiator enters the valve, the tubular members 18 and 21 will expand according to the degree of the heat, and should the degree be greater than the members can withstand, the said members, through expansion, will cause the valve stem to close the opening 9 of the valve seat 8, thus preventing the exit of the air from the radiator. On the other hand, when the radiator becomes air bound and the steam or water vapor cools, the tubular members will contract, thus opening the passage of the valve seat 8 permitting the air to find an exit through the passage 14. By means of the set screw 16 and disc support 15, the distance between the valve stem 24' and the outer portion of the opening 9 can be readily adjusted and by such adjustment for example should the valve stem be adjusted any great distance from the opening, the

expansion of the tubular members 18 and 21 will doubtlessly have to be greater in order to close the opening, or should the valve stem be adjusted nearer the opening, the expansion of the tubular members will doubtlessly be less than when the valve stem is farther away from said opening.

I have found by experience that by forming the vent of the cap 13 in the manner illustrated in Fig. 1, that the singing noise which accompanies the discharge of the air from the valve is greatly obviated, if not entirely, and also by this arrangement particles of dust are prevented from gaining entrance into the cap and settling around the valve seat until the passage of air through the opening of the valve seat is prevented, this being the case where the vent of the cap is formed in alignment with the opening of the valve seat.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claim.

Having described my invention what I claim as new and desire to secure by Letters Patent is:

An air valve of the class described including a casing having an air vent formed therein, tubular members disposed concentrically with respect to each other arranged within the casing, a thermostatic member 95 having means at one end controlling passage through the air vent and having a thread-bearing socket formed in the other end thereof, a disc member having a threaded stud for threaded engagement with the socket, a spring member having an end in abutment with the adjacent side of the disc adapted to compensate for excessive expansion of said members, and means carried by one of the tubular members affording a support for the spring member.

In testimony whereof I have signed my name to this specification in the presence of two subscribing witnesses.

THOMAS C. DE VORE.
